FLOATING DRY DOCK

Charles A. D. Bayley, New York, N. Y.

Application August 10, 1944, Serial No. 548,857

16 Claims. (Cl. 114—45)

My invention relates to a floating drydock and a method of making the same. More particularly it relates to a drydock that may be assembled from pontoon elements into a strong structure.

In my present invention cylindrical pontoon elements of wood are arranged side by side horizontally and transversely to the length of the ship to be supported and floated. There may be one layer or tier of a lengthwise series of transverse pontoon elements or two or more layers in superposed arrangement.

Each pontoon element of the series may be formed of a hollow cylinder closed by a suitable head at each end, or two such cylinders may be positioned end to end to form each pontoon element of the horizontal series. These cylinders may be of uniform construction and may be formed separately as standard or standardized pieces and assembled into a drydock structure. They are preferably of wood, or largely of wood.

On being assembled into a horizontal series the pontoon elements are secured to beams extending lengthwise of the dock, that is, lengthwise of a ship to be supported on the dock. These beams are preferably of reinforced concrete and molded in position.

The individual pontoon elements are rigidly secured to a pair of central beams by fastening members interlocking with the cylindrical walls of the pontoon elements. The ends of the pontoon elements at each side of the dock are also secured in longitudinal beams, preferably of reinforced concrete.

Side walls of vertical cylindrical pontoons, similar to the horizontal pontoons, may be arranged in longitudinal series at each side of the horizontal structure and may be supported and secured thereon. Each side wall may be provided with one or more series of vertical pontoons.

To reinforce the horizontal pontoon elements against bending stresses cross beams of reinforced concrete may be secured on the longitudinal beams below the horizontal pontoon elements.

The cylindrical walls of the pontoon elements may be formed of water-proofed plywood or of staves or partly of plywood and partly of staves. By the use of plywood in which the plies are joined or cemented by resins that are resistant to water and that are not water absorptive, structures of great strength and stiffness relative to weight are obtained and these structures are also resistant to deterioration in sea water. The cylindrical walls of the pontoon elements provide a maximum resistance to compression. They are

closed near their ends by dome shaped heads which also offer the maximum resistance to compressive forces. The cylindrical walls project beyond the dome shaped heads to provide means for mounting and securing the pontoons to the longitudinal beam structures.

The various features of the invention are illustrated by way of example in the accompanying drawings in which

Fig. 1 is a side view and Fig. 2 a plan view of a drydock embodying my invention and showing the position of a ship thereon;

Fig. 3 is an end view of the drydock;

Fig. 4 is a plan of one section of the drydock shown in Figs. 1 and 2;

Fig. 5 is a plan view on a larger scale of a part of the horizontal pontoons and the central longitudinal beam;

Fig. 6 is a vertical section on the line 6—6 of Fig. 4;

Fig. 7 is a section taken on the line 7—7 of Fig. 5;

Fig. 8 is a detail in section of the floor of the drydock;

Fig. 9 is a vertical section through the lower part of the side walls and the beam structure on which it rests, taken at a right angle to the section of Fig. 6;

Fig. 10 is a vertical section on the line 10—10 of Fig. 11 of the lower part of a vertical pontoon on a somewhat larger scale than that of Fig. 9;

Figs. 11 and 12 are horizontal sections taken on the line 11—11 of Fig. 10;

Figs. 13 and 14 are respectively plan and vertical sections of a detail of the side walls of the dock.

Referring more particularly to Figs. 1 and 2 a drydock is shown as being formed of a number of sections 20 arranged end to end to support a ship 21. Five such sections are shown in the particular embodiment illustrated but it will be understood that any required number may be employed depending upon the size of the sections and of the ship to be supported. Working platforms 22 and 23 are provided on the end sections of the drydock.

As shown in Figs. 3 and 4 each section 20 comprises a horizontal base or raft-like structure 24 between a pair of side walls 25 and 26, one at each side of the section.

As shown in more detail in Figs. 5 to 9 inclusive, the base or raft structure is formed of a series of horizontal cylindrical pontoon elements 27, 28, 29, 30, etc.

In the particular embodiment of the invention

shown in Figs. 6, 7 and 9, two such series of horizontal pontoon elements are provided, namely, an upper series or layer of the elements 27, 28, 29, 30, etc., and a lower layer made up of the elements 31, 32, 33, 34, 35, etc. It will be understood, however, that there may be one or more such layers, depending upon the size of the dock and of the respective cylinders.

The series of cylinders are united by longitudinal beams, there being two spaced mid beams 36 and 37 as shown in Fig. 5 and a pair of spaced side beams 38 and 39, one at each side of the dock, and there may be a number of spaced longitudinal floor beams such as those shown at 40, 41, 42, extending over the upper series of pontoons as shown, for example, in Fig. 7.

The several pontoon elements are secured to the longitudinal beams 36, 37, 38, 39, which unite the pontoons into a rigid unitary structure.

Each pontoon element is formed of a cylindrical wall 43 and dome shaped end closures or heads 44, one at each end, spaced inwardly of the end of the cylindrical wall to provide a projecting portion or extension 45. The cylindrical walls and the heads are preferably formed entirely or principally of wood, preferably of plywood in which several plies of shaped wood are united by a water resistant, waterproof resinous cement. Or these walls may be made of wooden staves or of staves and plywood structures. Such constructions form a structure having great resistance to compressive forces and also to bending moments.

Each of the horizontal pontoon elements is formed of a pair of closed cylinders arranged end to end and with the opposed ends abutting one of the mid beams 36 or 37. As shown in Fig. 5 the elements are preferably so arranged that one pair of cylinders will abut the beam 36 extending in opposite directions therefrom; one of the cylinders extending through the beam 37 while the next pair will abut and be secured to the beam 31, while the opposite cylinder extends through the beam 36 and in this way the series of cylinders is alternately secured to the longitudinal beams 36 and 37 and alternately passes through the other of these beams so as to break the joints longitudinally of the dock. The lower layer is similarly arranged and secured to the beams and the elements may be secured to the opposite beam from the element immediately above it as, for example, the element 27 may be secured to the beam 36, while the element 31 immediately beneath it may be secured to the beam 37, thus breaking joints vertically as well as longitudinally.

In the embodiment illustrated the elements of the lower layer are immediately beneath those of the upper layer but in some constructions may be staggered relatively thereto.

Similarly the outer ends of the cylinders may be secured either to the inner of the side beams 38 or may pass through this beam to be secured to the outer beam 39. For example one cylinder of the pontoon 27 may be secured to the beam 38 and the opposite one pass through the inner beam 38 on the opposite side and be secured to the outermost beam 39 thereof. It will thus be apparent that between the side beams 38 and 39 there are alternately pontoons and spaces in the upper series that extend between the beams 38 and 39. The lower series of cylinders all extend to the outer beam 39.

The vertical side walls 25 and 26 are formed of one or more series of vertical cylinders 46 and

47, Figs. 3 and 4, two being shown by way of example. Each of the series 46 and 47 comprises a number of vertical cylindrical pontoon elements 48, 49, 50, 51, etc., Fig. 6, similar in construction to the horizontal pontoon elements, that is, having cylindrical walls 43 and dome shaped heads 44. The vertical pontoons of each series are alternately longer and shorter, the shorter elements such as 48 and 50, Fig. 6, resting upon or above the horizontal pontoon elements 27 and 29 that extend between the longitudinal side beams 38 and 39, while the alternate vertical pontoons 49 and 51 extend in the spaces between the beams 38 and 39 and between the pontoon elements 27 and 29 to be supported immediately above the corresponding lower pontoon elements 32 and 34.

The vertical pontoons of the outer series 47 may extend upwardly and be connected to an upper platform 52 and similarly the inner series 46 may extend upwardly to a lower platform 53 which extends horizontally outwardly about the cylinders of the series 47 at a suitable distance below the platform 52 thus serving to rigidly join and reinforce the upper ends of the vertical pontoons.

The lower ends of the pontoons are supported on a concrete filling, indicated at 54 Fig. 6, between the side beams 38 and 39, this filling extending upwardly about those horizontal pontoons that projects between the side beams 38 and 39 but not into the spaces between the side beams and the projecting pontoon elements, such as 27 and 29; and correspondingly the vertical wall pontoons rest alternately on different levels as shown in Fig. 6, one level being above the upper layer of pontoons and the other below this layer and above the lower layer of pontoons. Thus the joints at which the vertical pontoons are secured to the horizontal raft structure are broken or staggered and given greater strength and rigidity.

The cylindrical pontoon elements of the vertical and horizontal series may be joined and secured to their respective beam, either the horizontal beams 36, 37, 38, 39, or to the filling 54 between the beams 38 and 39 by similar securing or locking means. This securing means is shown more particularly in Figs. 10, 11 and 12. As shown in these figures that part of the cylindrical wall 43 that projects beyond the dome shaped head 44 is reinforced by a collar 55 secured integrally to the wall 43.

Projecting inwardly from the collar 55 at spaced intervals are lugs 56, four being shown by way of example in Figs. 10 and 12. The aggregate circumference of these lugs will total somewhat less than one-half the circumference of the ring or collar 55 and they are equally spaced so that between each pair of lugs is a space of equal or approximately slightly greater width. Abutting or supporting the lower edge of the projecting wall 43 is a plate 57 of concrete when the longitudinal beams are of concrete. This plate 57 is slightly larger in area than the cross-sectional area of the walls 43 and may be of square or polygonal perimeter as shown in Figs. 11 and 12. It may be provided with projecting irons 58 to be molded or cast into the concrete beams as the latter are formed. A number of spaced projections 59 extend upwardly from the plate 57 of a circumferential width and of a diameter to pass upwardly between the lugs 56 and extending somewhat above these lugs. The outer vertical sur-

faces of these projections are cylindrical and fit closely against the inner surface of the ring or collar 55 as indicated in Figs. 10 and 12. They may thus be passed upwardly between the lugs 56 then in the position shown in Fig. 11. Each of the projections 59 is provided with a recess to receive the lugs 57 when the cylinder is given a turn relative to its base or plate 57 from the position shown in Fig. 11 to that shown in Fig. 12. The lugs 56 and projections 59, therefore, interlock in a manner similar to a bayonet joint or to the interrupted threads of a breech block. The cylinder may then be secured against rotating and unlocking by any suitable means.

Each of the projecting walls 43 and collars 55 may be provided with a manhole or door or opening 60, as shown in Fig. 12, through which the space between the plate 57 and the head 44 may be inspected at intervals.

The above construction is one that permits of an assembly of the various elements of the dock from standardized or uniform parts to form a very rigid strong construction but one that is relatively light for its size and strength.

In forming the structure it is only necessary that the end plates 57 be fitted on the respective horizontal cylinders 27, 35, one plate for each end, and that the opposite plates of each pair of cylinders forming one pontoon element as, for example, the cylinders of the pontoon element 27, be placed and spaced to receive the respective beams 36. And similarly the plates of the cylinders of the pontoon element 28 spaced and positioned to receive the longitudinal beam 31. When the cylinders have thus been placed and secured in position the beams 36 and 31 may be cast in position, using suitable forms, and thereby anchor the respective cylinders through their bases and through the anchorage 58 and also by being cast about those cylinders that project through one of the beams.

Similarly the side beams 38, 39, may be cast in position. In this way the elements of the lower or raft structure are united into a unit of longitudinal beams of reinforced concrete cast into position on the relatively light wood cylindrical pontoons. Thereupon the filling 54 is placed in position together with the plates 51 of the vertical cylinders after which these cylinders may be placed and locked in position by turning them as indicated in Figs. 11 and 12. Similarly the top plates may then be locked in position and built in the horizontal platforms 52 and 53.

To prevent warping of the pontoons between the longitudinal beams they may be braced by suitable bracing blocks as shown in Fig. 7. The several cylinders 27, 28 and 29, for example, of the upper layer or tier of pontoons may be spaced and braced by means of a pair of bracing blocks 61 and 62 between each adjacent pair of cylinders, these blocks being shaped to fit the curvature of the cylinders. The pair of blocks are suspended from the floor beams 40, 41 or 42 respectively by means of a threaded rod 63 anchored in the floor beam and extending downwardly through the block 61 and provided with an upper nut 64 and lower nut 65 which may be screwed in opposite directions against the respective blocks 61 and 62 to bring them tightly against the surfaces of their respective cylinders. A side beam 66 extends downwardly from each of the beams 40, 41, 42, being secured thereto at its upper end and being secured to a lower beam 67 below the lower tier of pontoons.

Bracing blocks 68 and 69 may be mounted between the cylinders 31, 32, 33 of the lower tier of pontoons and tightened by a bolt 70 extending downwardly into the lower beam 67. In this way the cylinders of the lower tier or layer may be held in proper spaced position.

Bracing blocks 71 and 72 are similarly mounted between cylinders of the upper and lower tiers and tightened by means of bolts 73; the outermost of these bolts may be extended to and secured in the side beams 66. By means of this bracing the cylinders may be held rigidly in uniform spaced position between the mid beams 36 or 37 and the outer beams 38. Similarly the lower tier of cylinders may be braced between the beams 38 and 39 by means of bracing blocks 74 and 75 and bolts 76 as shown in Figs. 6 and 9.

When a ship is in position on the drydock and the latter is floated the center of the upward lifting forces on the several pontoons will be at some distance from the mid beams 36 and 37 on which the weight of the ship is directly received. To reinforce the pontoons against the resultant bending forces transverse beams 77 may be mounted below the lowermost tier of pontoons and extend transversely across the pontoons and rigidly connected to the end beams and the mid beams. These transverse beams 77 may be of reinforced concrete cast integrally with the longitudinal beams or precast and secured to them during the formation of the dock. It will be apparent that the bending stresses will cause tension on the beams 77 so that the cylindrical walls of the pontoon will be required only to resist compressive stresses for which their structure is particularly suited.

The several horizontal and vertical pontoons will be provided with a piping system and pumps, such as indicated in dotted lines at 78 in Fig. 9, whereby the pontoons may be pumped free of water, or water may be admitted. Any suitable arrangement of piping and pumps may be employed and the system of piping is, therefore, not illustrated.

A floor made up of concrete slabs 79, Figs. 7 and 8, may be mounted on the floor beams 40 and secured thereto by means of bolts 80. The sections of the drydock may also be provided with wooden sides 81, as shown in Fig. 7, and with bottom planks 82 to protect the concrete from abrasion. Also the side walls may be protected by means of vertical buffering structures 83 of wood or timber secured in holding brackets 84 on the platforms 25 and 26.

Through the above invention I have provided a floating drydock that may be assembled from standard parts, namely cylindrical structures of standard sizes. These cylindrical structures may be fabricated at any suitable place, either at the shipyard or distant therefrom, and shipped and assembled where the dock is to be built. The concrete holding beams may then be cast in position. For example the cylindrical walls may be formed in semi-cylinders which may be joined at the place of construction, in the event that the dock is to be used at some distance from a shipyard or manufacturing center and the concrete structure may then be cast in place. It will be understood, however, that the sections of the dock may be towed from one place to another then joined end to end in the manner known in the art to form a complete dock.

The cylindrical pontoons need not be of circular cross-section but some, or all, of the pontoons

may be of other than circular cross-section. The word "cylindrical" is, therefore, not to be construed as applying only to cylinders of circular cross-section, although they are preferred in most constructions.

What I claim is:

1. A floating drydock which comprises a longitudinal series of transverse horizontal cylindrical wooden pontoons, each pontoon having dome shaped heads and walls projecting beyond said heads, end pieces locked to said projections of said walls and longitudinal beams secured to said end pieces.

2. A floating drydock which comprises a longitudinal series of transverse horizontal cylindrical wooden pontoons, each pontoon having dome shaped heads and cylindrical walls projecting beyond said heads, middle longitudinal beams to which said pontoons are secured, side walls comprising longitudinal series of vertical cylinders of wood having heads, said cylinders projecting beyond said heads, end pieces on which said cylinders are supported, means for securing said cylinders to said end pieces, spaced longitudinal side beams secured to said pontoons, and means for securing the supporting end pieces of said vertical walls on said horizontal pontoons between said side beams.

3. A floating drydock which comprises a longitudinal series of transverse horizontal cylindrical wooden pontoons, each pontoon having dome shaped heads and cylindrical walls projecting beyond said heads, the ends of said cylindrical walls being reinforced and having inwardly projecting lugs at regular intervals about their inner surface and end pieces of concrete having projections extending into said projecting cylindrical walls and having recesses to receive and interlock with said lugs.

4. A floating drydock having a horizontal base and having side walls, said side walls comprising a series of vertical wooden cylinders and closing heads therein spaced from the ends of said cylinders, the ends of said cylinders beyond said heads being reinforced and having lugs at spaced intervals projecting inwardly, the horizontal base of said drydock having upward projections at spaced intervals to fit into the inner surface of the projecting part of said wooden cylinders and having recesses to receive and interlock with the lugs of said cylinders.

5. A drydock which comprises a middle pair of spaced longitudinal beams of reinforced concrete and a longitudinal series of transverse horizontal cylindrical pontoon elements of wood, each of said pontoon elements comprising a pair of aligned closed cylinders secured to one of said beams on opposite sides thereof, one of said cylinders passing through the other of said beams, successive pontoon elements of said series being secured longitudinally to opposite beams of said pair.

6. A drydock which comprises a middle pair of spaced longitudinal beams of reinforced concrete and a longitudinal series of transverse horizontal cylindrical pontoon elements of wood, each of said pontoon elements comprising a pair of aligned cylinders having dome shaped heads spaced inwardly from the ends of said cylinders, the cylinders of each pontoon element being secured to one of said beams on opposite sides thereof, one of said cylinders passing through the other of said beams, successive pontoon elements of said series being secured alternately to the opposite beams of said pair.

7. A drydock which comprises a middle pair of spaced longitudinal beams of reinforced concrete and a series of transverse horizontal cylindrical pontoon elements of wood, each of said pontoon elements comprising a pair of aligned cylinders closed at a distance from the ends of said cylinders, the opposed ends of the cylinders of each pontoon element having end pieces interlocked with the ends of said cylindrical elements and secured to one of said beams on the opposite sides thereof, one of said cylindrical elements passing through the other of said middle beams, successive pontoon elements of said series being secured alternately to opposite beams of said pair.

15 8. A drydock which comprises a middle pair of spaced longitudinal beams of reinforced concrete and an upper and a lower series of transverse horizontal cylindrical pontoon elements of wood, each of said pontoon elements comprising a pair of aligned cylinders of wood closed near their ends, end pieces interlocking with the opposed ends of said cylinders and secured to one of said beams, one of said cylindrical elements extending through the other of said beams, successive pontoon elements of said series being secured alternately to opposite beams of said pair and each pontoon element of the lower series being secured to the other beam of the pair from that secured to the pontoon element of the upper series immediately thereabove.

20 9. A drydock which comprises a middle pair of spaced longitudinal beams of reinforced concrete and a longitudinal series of transverse horizontal cylindrical pontoon elements of wood, each of said pontoon elements comprising a pair of aligned cylinders closed at their ends, end pieces interlocked with the opposed ends of said aligned cylinders and secured to one of said longitudinal beams, one of the cylinders of said elements passing through the other of said longitudinal beams and spaced pairs of side beams secured to the ends of said pontoon elements.

25 10. The drydock of claim 9 and side walls of vertical closed cylinders of wood secured to said horizontal structure between side beams at each side of said drydock.

30 11. A drydock which comprises a longitudinal series of transverse horizontal cylindrical pontoon elements of wood, a mid pair of spaced longitudinal beams of reinforced concrete embedding and secured to said pontoon elements, two pairs of spaced longitudinal concrete beams, one pair at each side of said drydock embedding the ends of said pontoon elements, alternate pontoon elements ending at the inner side beam of said pair and vertical cylinders of wood between the side beams of each pair of longitudinal beams, the lower ends of successive vertical cylinders being supported alternately on and between the horizontal pontoon elements between said side beams.

35 12. A drydock having longitudinal beams, plates secured to said beams and having projections and cylinders ended on said plates, said cylinders having heads spaced inwardly from the ends thereof and having lugs interlocking with the projections of said plates.

40 13. The structure of claim 12 in which said heads are dome shaped.

45 14. A floating drydock which comprises a longitudinal series of transverse horizontal cylindrical wooden pontoons and longitudinal beams of reinforced concrete embedding said pontoons and uniting said pontoons in a unitary structure.

15. A floating drydock which comprises a longitudinal series of transverse horizontal cylindrical wooden pontoons and longitudinal beams of reinforced concrete embedding said pontoons and uniting said pontoons in a unitary structure and braces between the lengths of successive pontoons between said longitudinal beams.

16. A floating drydock which comprises a longitudinal series of transverse horizontal cylin-

drical wooden pontoons, a pair of mid longitudinal beams of reinforced concrete embedding mid portions of said pontoon elements, a reinforced concrete beam at each side of said drydock embedding the end portions of said pontoons and a transverse beam of reinforced concrete below said pontoon elements and secured to said mid and side longitudinal beams.

CHARLES A. D. BAYLEY.
